UNITED STATES PATENT OFFICE.

IGNATZ GOLDBERGER, OF CLEVELAND, OHIO.

DESIGN FOR AN UNDERGARMENT.

SPECIFICATION forming part of Design No. 26,547, dated January 19, 1897.

Application filed December 23, 1896. Serial No. 616,814. Term of patent 14 years.

To all whom it may concern:

Be it known that I, IGNATZ GOLDBERGER, a citizen of the United States, and a resident of Cleveland, in the county of Cuyahoga and State of Ohio, have invented and produced a new and original Design for Undergarments, of which the following is a specification, reference being had to the accompanying drawings, forming a part thereof.

10 Figure I is a front elevation of an undergarment representing a combination-suit and showing my design, the central flap and shoulder-flaps being open and detached to expose the chest-opening, which extends across the body. Fig. II is a back view thereof. Fig. III is a front view of the undergarment, the flaps being closed. Fig. IV is a back view thereof.

15 The leading feature of my design consists 20 in the peculiar configuration of the upper part of the undergarment, which has three angular-shaped flaps located over the chest-opening, so as to cover the same, the central flap being in the form of a wedge-shaped 25 tongue of the width of the body portion at the base of the tongue and projecting upwardly and the shoulder-flaps being in the form of an approximately rectangular figure and pro-

jecting downwardly and resembling in shape a cape extending beyond the sides of the body 30 in front of the inner portion of the arms.

Referring to the drawings, it will be seen that the two shoulder-flaps when detached and opened project upwardly, and the central flap when opened projects downwardly from 35 the chest-opening, which extends across the body portion of the undergarment. The shoulder-flaps are angular in shape, representing approximately two rectangular figures, and the central flap is also angular in 40 shape, representing a broad tapering tongue of the width of the body portion at the base of the tongue. When the flaps are closed, the shoulder-flaps form a broad inverted-V-shaped space over the central flap between 45 the shoulder-flaps.

Having thus described my invention, the following is what I claim as new therein and desire to secure by Design Letters Patent:

The design for an undergarment, substantially as herein shown and described.

IGNATZ GOLDBERGER.
